UNITED STATES PATENT OFFICE.

ALDO PAVESI, OF NEW YORK, N. Y.

NON-REFILLABLE BOTTLE.

1,161,328.

Specification of Letters Patent. Patented Nov. 23, 1915.

Application filed April 30, 1914. Serial No. 835,365.

To all whom it may concern:

Be it known that I, ALDO PAVESI, a subject of the King of Italy, and residing at New York, in the county of New York and State 5 of New York, have invented certain new and useful Improvements in Non-Refillable Bottles, of which the following is a specification, such as will enable those skilled in the art to which it appertains to make and use the 10 same.

This invention relates to bottles, jugs, jars and similar vessels, and the object thereof is to provide a vessel of this class having a neck with a neck attachment or construction, 15 whereby when the vessel has once been filled and closed or sealed, it may be emptied of its contents, but cannot be refilled or reused.

The invention is fully disclosed in the following specification, of which the accompanying drawing forms a part, in which the 20 separate parts of my improvement are designated by suitable reference characters in each of the views, and in which:—

Figure 1 is a central vertical section 25 through the neck of a bottle or similar vessel provided with my improvement;—Fig. 2 a similar view but showing the bottle or vessel inverted;—Fig. 3 a side view of a valve which I employ, and which is shown in section in Figs. 1 and 2.

In carrying my invention into effect, as shown in Figs. 1, 2 and 3, I provide a bottle or vessel of the class specified having a neck a within the top portion of which is an annular enlargement a^2 forming an inner annular shoulder a^3 which constitutes a valve seat having a port or passage a^4 through which the contents of the bottle or vessel 35 may be discharged and on which is placed a cup-shaped valve b the bottom surface of 40 which is formed on the arc of a circle and is adapted to close the port or passage a^4 .

The rim of the valve b is provided with raised lugs or projections b^2 , any desired 45 number of which may be employed, and but four of which are shown, and the body portion of said valve is provided with laterally or radially directed lugs or projections b^3 , four of which are preferably employed.

I also provide the neck of the bottle or vessel with a closure cap c having a depending skirt or rim c^2 which fits in the annular 50 enlargement in the top of the neck, and said cap is provided centrally with a tubular discharge c^3 having, in the form of construction shown, a raised collar or rim c^4 and in

the bottom of the tubular discharge c^3 is a spider-work or transverse portion c^5 having ports or passages c^6 any desired number of which may be employed, and said cap is held 60 in place or secured to the neck by a band d of flexible sheet metal or similar material.

The rim c^2 of the cap c forms a valve chamber c^7 in which the valve b is freely movable within certain limits, and the greatest diameter of said valve is slightly less than the chamber in which it is placed, the proportions of said parts being relatively such that while the valve is freely movable within certain limits, it is always in position 65 for use, and cannot be inverted or turned over, and the lugs or projections b^3 on the body of the valve and the lugs or projections b^2 on the top or rim portion of the valve facilitate the operation thereof and 70 hold it in proper position at all times.

In the use of a bottle of this class, it is first filled with the desired contents, after which the valve is placed in position, after which the cap c is secured in place, after 75 which the tubular passage c^3 in the top portion of said cap is closed by a cork or stopper, in the usual manner, and when it is desired to pour out the contents of the bottle, or discharge a portion thereof, the cork or 80 stopper is removed and the bottle inverted, as shown in Fig. 2. In this position of the bottle, the valve b moves downwardly or 85 forwardly and rests on the annular shoulder c^8 and the contents of the bottle will flow 90 out freely around the valve and through the ports or passages c^6 , as will be readily understood, and this operation may be continued or repeated until the bottle is entirely 95 emptied.

If an attempt be made to refill the bottle by pouring liquids thereinto, the valve b will assume the position shown in Fig. 1 and no liquids can enter the bottle, and if an attempt be made to force liquids into the bottle when said bottle is held in the position shown in Fig. 2, the said valve will rise 100 to its seat a^3 and no liquids can enter the bottle.

Of course, the valve b may be made of 105 any preferred material, as may also the cap c , but said parts are preferably made of glass or porcelain.

The top rim portion of the valve b is of greater diameter than the tubular discharge 110 c^3 through the cap c , and the position of said valve in the construction shown, is such

that a wire or instrument of any kind or class could not be inserted through the ports or passages c^6 and successfully used in an effort to interfere with the operation of the 5 valve as described, and other changes in and modifications of my improvement may be made, within the scope of the appended claim, without departing from the spirit of my invention or sacrificing its advantages.

10 Having fully described my invention, what I claim as new and desire to secure by Letters Patent is:—

15 A bottle or similar vessel provided with a neck within the top portion of which is an annular valve seat on which is placed a cup-shaped valve movable longitudinally of the neck, and a closure cap secured on said neck and having a central discharge in the bottom of which is a transverse member having 20 ports or passages, said central discharge being provided with a depending annular skirt

portion adapted to bear on said annular valve seat, the rim portion of said valve being of greater diameter than said transverse member and being provided with raised lugs 25 or projections and the body of said valve being also provided with lateral lugs or projections which form guides therefor in its movement in the neck, the outward movement of said valve being limited by said transverse member so as to permit a continuous flow of the contents of said bottle through said neck and said discharge.

In testimony that I claim the foregoing as my invention I have signed my name in 35 presence of the subscribing witnesses this 29th day of April, 1914.

ALDO PAVESI.
